CENTRIFUGAL ABRASIVE BLASTING
MACHINEJohn E. Guendling, South Bend, Ind., assignor to
The American Foundry Equipment Company,
Mishawaka, Ind., a corporation of Delaware

Application June 25, 1938, Serial No. 215,753

4 Claims. (Cl. 51—9)

This invention relates to centrifugal abrasive blasting machines and more particularly to an abrasive throwing wheel having improved abrasive supply means associated therewith whereby increased abrasive capacity and operating efficiency of this unit of the machine may be realized.

Centrifugal abrasive throwing wheels of the type now in general use comprise a rotor head mounted upon a high speed shaft, the rotor head having a plurality of spaced substantially radially extending abrasive throwing blades mounted thereon, the blades extending inwardly short of the axis of the rotor to provide a central space within which a device for controlling the direction of discharge of the abrasive is positioned. To reduce windage and consequent loss of power, the blades may be positioned between and supported by the rotor head and a side wall plate which are rigidly secured together. The control device comprises a tubular member inserted into the central space within the wheel, which tubular member is supported in relatively stationary position and is provided with a discharge opening in the peripheral wall thereof through which the abrasive is discharged onto the inner ends of the blades as they successively rotate past the discharge opening. Means, such as a bladed impeller fixed to the rotor head, is provided for forcibly projecting the abrasive fed into the tubular control member through the discharge opening thereof. The abrasive material generally used in abrasive throwing machines of this type comprises steel shot or steel grit and occasionally hard quartz sand.

Means must be provided for conducting this abrasive material into the tubular control member in such manner that it will be properly projected by the impeller through the discharge opening in the side wall of the tubular control member. Abrasive throwing wheels of this general type are normally constructed from eighteen to twenty inches in diameter and are rotated at a speed of 2200 to 2600 R. P. M., developing a peripheral velocity of from 11,000 to 15,000 lineal feet per minute. It will be appreciated that when a wheel having eight blades and constructed as above indicated is rotated at 2200 R. P. M., a blade will move past the discharge opening in the control member over 17,000 times every minute. Thus, even when very large quantities of abrasive are fed into the control member, only a small quantity of abrasive will be ejected into the inner end of each blade as it passes the discharge opening therein. Assuming, for example, that a cubic

foot of steel grid abrasive, which weighs approximately 350 lbs. is fed per minute into an eight-bladed wheel approximately twenty inches in diameter and rotating at 2200 R. P. M.—in feeding this quantity of abrasive into the wheel approximately only $\frac{1}{6}$ of a cubic inch of abrasive would be fed onto each throwing blade during each revolution thereof, which small charge is ejected from the blade before a second charge is placed thereon.

It will thus be appreciated that the capacity of an abrasive throwing wheel is to a large extent controlled by the amount of abrasive which can be conducted into and fed into the rotating impeller within the tubular control member. The throwing blades in the wheel should preferably be made of substantial length so that the abrasive may be picked up on the inner end of each blade while the abrasive is moving at a relatively low velocity and thereafter may be gradually accelerated as it moves along the face of the blade until it has gained an abrading velocity of 11,000 to 15,000 lineal feet per minute as it leaves the outer end of the blade. Thus, it is appreciated that the diameter of the tubular control member as well as the impeller positioned within the tubular control member must be made relatively small. The abrasive can be most effectively conducted into the path of rotation of the impeller vanes by providing a central opening in the impeller into which the abrasive is conducted by the feed spout. However, the diameter of the feed spout through which the abrasive moves by gravity must then be no greater than the diameter of the central open space within the impeller and consequently the inside diameter of the feed spout is correspondingly limited. Furthermore, the feed spout should not be completely filled with abrasive since this would result in a definite retardation of the velocity flow through the feed spout and into the impeller and an actual decrease in the amount of abrasive conducted into the impeller measured in pounds per minute.

I have discovered that improved operating results and a substantial increase in abrasive capacity are accomplished by providing an air vent opening adjacent the discharge end of the feed conduit, which air vent opening is guarded by a baffle which prevents the abrasive flowing through the feed conduit from falling out or discharging from the vent opening. The feed capacity of the feed spout may thus be increased from 20% to 50% and upwards. The air vent adjacent the discharge end of the feed conduit

also prevents the settling of the fine abrasive particles and dust along the interior lower wall of the feed conduit as often occurs in the prior art structures. Further, the air vent effects a 5 thorough mixing of the fine and coarse abrasive particles and also effects a more uniform flow of abrasive through the wheel and a more even distribution of abrasive over the full width of the throwing blades.

10 An object of this invention is to provide a centrifugal abrasive throwing wheel having associated therewith improved abrasive supply means whereby increased abrasive capacity and abrading efficiency may be attained.

15 Another object of this invention is to provide an improved means for supplying abrasive to a centrifugal abrasive throwing wheel whereby settling of the fine abrasive material in the feed supply means is prevented and a uniform mixing 20 of the fine and coarse abrasive particles injected into the wheel may be obtained.

A further object of this invention is to provide an improved feed spout for conducting the abrasive into an abrasive throwing wheel whereby 25 the abrasive-feeding capacity of the feed spout may be substantially increased without an increase in the diameter, the gravity drop or the length thereof.

Other objects of this invention will become apparent as the disclosure proceeds.

30 Various other features and advantages of the invention will become apparent as the disclosure proceeds.

Although the novel features which are believed 35 to be characteristic of this invention will be particularly pointed out in the claims appended hereto, the invention itself, as to its objects and advantages, and the manner in which it may be carried out, may be better understood by referring 40 to the following description taken in connection with the accompanying drawings forming a part thereof, in which

Fig. 1 is a front elevational view of a centrifugal abrasive throwing wheel showing my improved 45 spout for supplying abrasive to the wheel associated therewith;

Fig. 2 is a transverse cross-sectional view of the centrifugal abrasive throwing wheel and associated abrasive supply conduit, this view being 50 taken on line 2-2 of Fig. 1;

Fig. 3 is an enlarged front elevational view of the improved feed spout;

Fig. 4 is an enlarged side elevational view of the improved feed spout;

55 Fig. 5 is an enlarged top plan view of the improved feed spout, certain parts being broken away to more clearly illustrate the internal construction thereof; and

Fig. 6 is an enlarged fragmentary cross-section- 60 al view of the feed spout adjacent the discharge end thereof, this view being taken on line 6-6 of Fig. 3.

Similar reference characters refer to similar parts throughout the several views of the drawings and the specification.

For a better understanding of this invention, there is shown in Figs. 1 and 2 one type of abrasive throwing wheel with which my improved abrasive supply means may be associated. The 70 wheel comprises a rotor head 1 which may be suitably mounted upon a high speed shaft 2 by means of a hub 3 which is keyed to the shaft and secured to the rotor head 1 by bolts 4. Channel-shaped abrasive throwing blades b, shown in Figs. 75 1 and 2, are provided which are radially arranged

in spaced relationship and are suitably mounted to rotate with the rotor head 1. To reduce windage and provide a convenient support for the blades b, a generally circular side wall plate 5 is provided substantially equal in size to the rotor head 1, the rotor head 1 and the side wall plate 5 being rigidly held and secured together in fixed parallel spaced relationship by suitable shouldered stud elements 6, the ends of which are fixedly secured to the rotor head 1 and side wall plate 5. The blades b may be suspended between the rotor head 1 and the side wall plate 5 by the provision of parallel extending grooves 7 in the rotor head 1 and the side wall plate 5, within which the side edges of the blades b extend and are supported.

Each of the blades b is generally channel-shaped in transverse cross-section and comprises a bottom wall portion 100 and side flange portions 101 which extend forwardly in the direction of 20 rotation of the rotor. The flange portions 101 serve to confine the abrasive flowing over the blade between the flanges 101 and on the bottom wall 100 of the blade. The blades extend substantially from the outer periphery of the rotor head 1, inwardly along a substantially radial line to a point spaced from the axis of rotation of the wheel so as to provide a central space 8 within which a tubular control member 10 extends. Each of the blades b may be held in position by a suitable set screw 9 which is screwed into a threaded aperture in the side wall plate 5, the inner end 9a of the set screw being tapered so as to seat within a corresponding shaped recess 9b provided in the side edge of the blade b. Each blade b may be removed when worn by retracting the set screw 9 and drawing the blade outwardly through the periphery of the wheel. The position of the inner end of the blade when located in the wheel may be fixed and determined by a centering plate 11, which is generally circular in shape and is so located that the outer edge 12 thereof overhangs the adjacent inner ends of the blades b so as to provide an abutment which limits the distance the blades may be inserted into the 45 wheel. The centering plate 11 may be fixed to the rotor head 1 by means of a pair of dowel pins each seating within corresponding shaped alined holes cut in the centering plate 11 and the hub 3.

50 The tubular control member 10 is provided with a discharge opening 15 in the tubular side wall 14 thereof, the side edges of the opening 15 being confined between the flanges 101 of the blades b. The opening 15 is preferably of limited 55 peripheral length, extending around the tubular wall 14 of the control member a distance approximately 30° to 90°. The tubular control member 10 is rigidly supported in stationary position during operation of the wheel upon a suitable supporting member 16 to which the tubular control member may be secured as by bolts 17 extending through elongated slots 18 in that portion of the tubular wall 14 of the control member 10 which extends exterior to the side wall plate 5. 65

The abrasive fed into the tubular control member 10 is forcibly ejected through the discharge opening 15 thereof by means of an impeller 20 which may comprise spaced side wall plates 21 and 22 having impeller vanes 24 extending there- 70 between. Preferably, the impeller vanes 24 are equal in number to the throwing blades b, each vane being positioned in the wheel slightly in advance of its corresponding throwing blade. The impeller vanes 24 also preferably extend in- 75

wardly short of the axis of the rotor so as to provide a relatively small abrasive admitting space 25. The impeller 20 is fixed to rotate with the rotor head 1, by means of a threaded securing bolt 26 which extends through the side wall plate 21 of the impeller and is screwed into a threaded hole in the end of the shaft 2. The rear face of the side wall plate 21 may be provided with a transverse rib 27 which seats within a corresponding slot 28 provided in an inwardly projecting circular boss 29 provided on the wear plate 11. Thus the impeller vanes 24 are held properly centered with respect to the discharge opening 15 in the tubular control member 10. The tubular control member 10 may be provided with an inwardly extending lip 13 which seats behind the impeller 20 and overlaps the rear side wall 21 thereof. The front wall plate 22 of the impeller is provided with a central opening 23 for the admission of the abrasive into the central space 25 within the impeller.

In an abrasive firing wheel of the type above described, it will be appreciated that the wear exerted by the abrasive on the parts of the machine is dependent upon the speed at which the abrasive is moving at that particular point. It is desirable to reduce the wear on the impeller 20 and the tubular control member 10 to a minimum and to concentrate the wear as much as possible on the removable and replaceable throwing blades b. To effect this desired result, the diameter of the tubular control member 10 should be kept to a minimum and for practical purposes should be in the nature of four and not over six inches in diameter. The abrasive throwing blades b can thus be correspondingly increased in length and in practical operation are generally made from five to eight inches in length. It will thus be appreciated that with a tubular control member 10 of relatively small diameter, the diameter of the impeller 20 is correspondingly small and for practical uses is generally 3½ to 5½ inches in outside diameter. Furthermore, the impeller vanes 24 of the impeller 20 must be of sufficient length to pick up the abrasive ejected over the inner ends thereof and to forcibly throw it out through the discharge opening 15, so that the diameter of the open space 25 within the impeller should preferably be kept within two to three inches in diameter. With the central feeding space 25 within the impeller thus definitely limited, it will be appreciated that the discharge end of the feed spout 31 which conducts the abrasive into the impeller must be kept within the diametrical limits of the central space 25 of the impeller and its diameter also is definitely limited.

Since the impeller side wall 22 is set a substantial distance within the outer edge of the tubular control member 10, it is necessary that the abrasive supply conduit 31 which conducts the abrasive into the impeller be provided with a bend to avoid obstructing the rotating wheel. Thus a straight gravity drop of the abrasive through a truly vertical feed spout is not possible. Furthermore, due to the break-up of the abrasive particles resulting from the terrific impact shocks the abrasive receives in striking the metal articles under treatment, the abrasive is gradually reduced in size, which fine abrasive is re-cycled through the feed spout and into the wheel. The abrasive "fines" or dust have a tendency to pack or settle along surfaces with which it comes into contact, with the result that there is a decided tendency for the abrasive fines to settle along the

lower interior face of the feed spout 31 where it departs from the vertical drop, which obstructs the free flow of the abrasive into the central receiving space 25 of the impeller.

I have discovered that the abrasive-feeding capacity of the feed spout 31 which conducts the abrasive into the wheel may be substantially increased by providing an air admission opening in the lower side wall of the feed spout at a point adjacent to the discharge end thereof or at points 10 where it departs from a vertical drop. As shown in Figs. 1 to 6 inclusive of the drawings, the feed spout 31 is of generally tubular form having a generally circular inside contour. The feed spout 31 may be rigidly supported upon a suitable bracket 32 affixed thereto, which bracket may be secured to a rigidly supported standard 33 as by bolts 34. The discharge end 35 of the feed spout 31 is centered with respect to the central receiving space 25 of the impeller 20, and may be provided with an outwardly flared lip or flange 36 which overlaps the side wall plate 22 of the impeller and is positioned closely adjacent to the side wall plate 22 with sufficient clearance only as not to obstruct the free rotation of the impeller 20. The flange 36 should also extend substantially to the interior surface of the tubular control member 10. The abrasive is supplied to the receiving end 37 of the feed spout 31 by a funnel 38. The funnel 38 is supported by a bracket 39 fixed thereto, which bracket is secured as by bolt 40 to the standard 33. The upper end of the feed spout 31 may be provided with outwardly flared ears 41 and the bracket 39 may also be provided with corresponding outwardly flared ears 42 through which securing bolts 43, as shown in Fig. 1, may extend and thus secure the feed spout 31 to the bracket 39.

Abrasive may be supplied to the funnel 38 by a supply line 44 leading from the abrasive elevator (not shown) to the funnel. The volume of discharge from the supply line 44 may be controlled by a gate 45 hinged to swing on the end of the supply line 44 as by pins 46. A suitable baffle plate 47 may be positioned within the funnel to prevent spillage of the abrasive leaving the line 44 and emptying into the funnel 38. The open mouth of the funnel 38 may be covered by a suitable wire mesh screen 50 which collects particles of metal and other foreign matter cycled through the abrasive supply system, preventing such foreign matter from entering the abrasive supply pipe 31 and passing into the rapidly rotating wheel. The screen 50 is of sufficient mesh to freely pass the abrasive particles ejected from the supply line 44. The abrasive dropped into the funnel 38 passes from the funnel into the feed conduit 31 and thence into the impeller 20.

To control the abrasive flow from the funnel 38 into the feed pipe 31, a gate 51 may be provided which slides within a corresponding slot 52 cut through the bracket 39 and the wall of the funnel 38. The gate 51 is provided with an aperture 53 of such size as to pass the desired amount of abrasive. The aperture 53 during operation of the wheel is positioned over the receiving mouth 37 of the feed pipe 31. The abrasive flow into the spot 31 may be cut off by shifting the slide gate 51 so as to close off the receiving end 37 of feed pipe 31.

The abrasive-conducting capacity of the feed pipe 31 having a predetermined diameter may be substantially and measurably increased by the provision of an opening 55 extending through 75

the lower inclined wall of the feed conduit 31 for the admission of a stream of air *a* which will flow into the wheel along with the abrasive. As shown more particularly in Figs. 3 to 6 inclusive, the air inlet opening 55 may be formed by cutting a V-shaped opening in the lower wall or belly of the feed conduit 31. The opening may thus be defined by a generally upwardly extending edge 56 and a generally horizontally extending edge 57 defining therebetween an air inlet area of approximately $\frac{1}{4}$ to $1\frac{1}{2}$ square inches. The opening 55 is further defined by a shelf 58 which extends towards the wheel and over which the abrasive flows, the shelf being of sufficient length to overlap the opening 55 so as to prevent the abrasive *g* sliding down the inside face or belly of the feed pipe from falling out through the opening 55. The shelf or baffle 58 merges into the tubular wall of the feed conduit 31, as fully illustrated in Figs. 3 to 6 inclusive.

When the abrasive throwing wheel is equipped with a feed conduit having an air inlet opening 55 protected by a baffle 58, unexpected and substantially improved operating results are obtained. It has been found that the abrasive-conducting capacity of the feed conduit of a predetermined size may be increased from 20% to 50% by the provision of an air inlet opening and associated baffle of the type heretofore described. The air stream *a* drawn through the opening 55 by the suction effect produced by the rapidly rotating wheel breaks up and destroys any tendency of the abrasive fines and dust to settle in the conduit. The settling of dust and abrasive fines in the conduit, which has the effect of slowing the abrasive flow through the feed conduit, is thus overcome.

By means of the feed conduit herein described, the abrasive is fed into the impeller with greater uniformity and is more evenly distributed over the impelling vanes 24 thereof, resulting in a more even distribution or spread of the abrasive over the entire width of the advancing face of the bottom wall 100 of the blade and a more uniform distribution of the thrown abrasive over the workpiece. The blades are also worn more uniformly and consequently have increased wear life.

The air vent or inlet opening 55 need not be limited to the particular shape shown in Figs. 3 to 6 inclusive but may assume other shapes. Further, one or more air inlet openings may be located along the lower wall or belly of the feed pipe at such points as there appears to be a tendency for the abrasive fines to settle or where the flow velocity of the abrasive becomes reduced. The shelf or baffle 58 may be concave, convex or substantially flat in cross-sectional contour, and should be so constructed as to permit the abrasive to flow freely thereover and to permit the free entry of a stream of air flowing in the direction of the abrasive throwing wheel. Preferably, the air inlet 55 should be positioned along the lower side wall or belly of the conduit so that the abrasive will flow over the inlet and the stream of air will flow inwardly into the conduit and generally under the abrasive stream flowing over the baffle 58.

It will be appreciated that the improved abrasive feeding means herein disclosed may be associated with abrasive throwing wheels of different sizes and modified forms, and that the wheel shown in Figs. 1 and 2 of the drawings is presented only as an illustration of one type 75 of abrasive throwing wheel in which my im-

proved abrasive supply means may be advantageously associated.

While certain novel features of the invention have been disclosed herein, and are pointed out in the annexed claims, it will be understood that various omissions, substitutions and changes may be made by those skilled in the art without departing from the spirit of the invention.

What I claim is:

1. In combination with a centrifugal abrasive throwing wheel having rotatably mounted abrasive throwing blades, a normally stationary tubular control member having a discharge opening in the side wall thereof adapted to direct abrasive onto the inner end of the rotating blades, and an impeller having impelling vanes positioned within said tubular control member and fixed to rotate with said blades, of means for supplying a stream of abrasive particles to said impeller for ejection by said impeller through said discharge opening in the tubular control member and onto the inner end of said blades, said abrasive supply means including an abrasive supply pipe arranged in inclined position having the lower discharge end thereof closely adjacent to said impeller, an air admission opening in said abrasive supply pipe located in the underside of said abrasive supply pipe immediately above a lower substantially horizontally extending discharge portion thereof, and a guard adjacent said opening operative to guide the flowing abrasive over said air admission opening and prevent the abrasive from escaping therethrough.

2. A centrifugal abrasive throwing machine including, a rotor head mounted to be rotated at high speed, radially arranged abrasive throwing blades mounted on said rotor head, a normally stationary control member having a discharge opening therein positioned to direct abrasive into the path of rotation of said blades a rotatably mounted impeller positioned within said control member operative when rotated to eject abrasive through the discharge opening in said control member, and means for supplying abrasive particles to said impeller, said abrasive supply means including an inclined abrasive supply conduit extending from a point above said impeller downwardly to a point adjacent said impeller, a funnel adjacent the upper end of said supply conduit, said conduit having an air admission opening located in the underside of said discharge end thereof, and a shelf element within said conduit overhanging said opening, said shelf element being operative to guide the abrasive flowing down the conduit over said air admission opening and prevent the abrasive from escaping through said opening.

3. A centrifugal abrasive throwing machine including, a plurality of spaced rotatably mounted abrasive throwing blades, a normally stationary tubular control member having a discharge opening therein through which abrasive may be conducted into the path of rotation of said blades, a rotatably mounted impeller within said tubular control member, an abrasive-receiving hopper positioned above said impeller, an abrasive supply conduit extending from said hopper downwardly to said impeller, means for controlling the flow of abrasive from said hopper through said supply conduit, said conduit having an air admission opening located in the underside and immediately above a curved generally horizontally extending discharge portion thereof, and a shelf element within said conduit overhanging said opening, said shelf element bei-

operative to guide the abrasive flowing down the conduit over said air admission opening and prevent the abrasive from escaping through said opening.

- 5 4. A centrifugal abrasive throwing machine including, a plurality of spaced rotatably mounted abrasive throwing blades, a normally stationary tubular control member having a discharge opening therein through which abrasive may be conducted into the path of rotation of said blades, a rotatably mounted impeller within said tubular control member, a gravity feed abrasive

supply conduit extending from a point above said impeller to said impeller, and means for increasing the volumetric abrasive-conducting capacity of said feed conduit, said means comprising an air intake port in said conduit located in the underside and adjacent the discharge end thereof, and an element overhanging said port operative to guide the abrasive flowing down said conduit over said port and prevent the abrasive from escaping through said port. 5 10

JOHN E. GUENDLING.
